UNITED STATES PATENT OFFICE.

HARRY D. JOHNSON, JR., OF SOUTH BEND, INDIANA.

LOCKING MECHANISM FOR DUMP-WAGONS.

1,127,444.

Specification of Letters Patent. Patented Feb. 9, 1915.

Application filed December 18, 1913. Serial No. 807,418.

To all whom it may concern:

Be it known that I, HARRY D. JOHNSON, Jr., citizen of the United States, residing at South Bend, in the county of St. Joseph and State of Indiana, have invented certain new and useful Improvements in Locking Mechanism for Dump-Wagons, of which the following is a specification.

This invention relates to improvements in locking mechanism for dump-wagon windlasses, and has for its particular object, to provide a lock for the windlass wherein the strain imposed upon the locking-pawl by the tendency of the windlass to unwind, caused by the weight of the load, is exerted upon a solid support and not upon the pivots of the pawl or its supporting arm.

A further object is to provide a device of this character, wherein the pawl is locked into engagement with the windlass ratchet and pivoted to operate over the ratchet when fixed in this position.

These and other objects hereinafter set forth, are attained by the means illustrated in the accompanying drawing, in which:

Figure 1, is a side elevation of the improved locking mechanism showing the windlass in cross-section. Fig. 2, is a central vertical longitudinal section through the locking pawl the same being shown on its support. Fig. 3, is an end view of the locking-pawl showing its support in section, and Fig. 4, is a detail perspective view of the locking-lever.

Similar reference numerals in all of the figures of the drawing designate like parts.

This device is adapted to be located in the foot-pit of dump-wagons, and comprises a supporting plate 5, a locking-pawl 6, a pawl-lever 7, and a lock 8, so positioned to the usual chain windlass, that the locking-pawl can be thrown into engagement with the ratchet 9, to prevent its reverse rotation.

The windlass 10 extends from side to side of the wagon-body, and is supported in any well known manner to rotate and wind the usual chains which close the dumping doors of the wagon, and said windlass is operated in the winding direction by the usual hand-lever 11, which is provided with the well known hand operated pawl 12.

Supporting plate 5 is secured to one side of the wagon-body and to the bottom, by the bolts 13, and is formed with a vertical

extension 14 having a curved upper surface 55 15, upon which is formed a rib 16, that is curved correspondingly to the surface 15.

Locking-pawl 6 is formed with an under curved surface 17 and provided with a curved longitudinal groove 18, said groove 60 and under surface being curved to conform to the surface 15 and rib 16 of the extension 14. Said pawl 6 is adapted to slide back and forth on top of the extension into and out of engagement with the ratchet 9, which 65 is in alignment therewith, and it is operated by the pawl-lever 7, which is pivoted at 18 to the supporting plate 5, and is provided with a vertical arm 19 and a substantially horizontal arm 20. The curved surfaces 15, 70 17, the rib 16 and the groove 18 of the plate 5 and pawl 6, are curved on a radius from the pivot 18 of the pawl-lever. Thus as the lever is rotated on its pivot, the upper end of the arm 19 moves back and forth carrying 75 the pawl 6 therewith, the same being pivotally secured thereto by the pin 21.

The groove 18 in the pawl 6, inclines upwardly and forwardly at the front end thereof as indicated at 22, so that it can tilt 80 on its pivot to ride over the teeth of the ratchet 9, and is also provided with extensions 23 which are adapted to engage the surfaces 15 to prevent the overturning of the pawl. Arm 20 of the locking-lever is somewhat longer than the arm 19 and extends toward the front end of the wagon. It is provided with a flat portion 24, which is adapted to be engaged by the foot of the operator to initially release the pawl from 90 the ratchet, and when released, the weight of the arm 20 will carry the pawl farther in the releasing direction.

To lock the pawl 6 in an operative position the lock 8 is provided, the same being 95 pivoted at 25 to the supporting plate 5, and comprises a locking lug 26 which is adapted to engage the under-side of the arm 20, a forwardly extending arm 27 having a projection 28, and a stop-lug 29 which is 100 adapted to engage a stop 30, preferably formed on the supporting plate 5. The lug 26 lies in alignment with the arm 20, and the arm 27 is offset therefrom, as clearly shown in Fig. 4, so as not to engage the arm 20 105 when the lug 26 is thrown to an unlocked position. Preferably the top of the lug 26 and the under surface of the arm 20 for a

portion of its length, is curved from a radius from the pivot center 25, to form a good bearing surface between the coöperating parts.

5 In operation, assuming that the parts are relatively positioned as shown in the drawing with the door chains, not shown, unwound, a movement of the windlass clockwise will wind the chain, and the pawl 6 10 will tilt on its pivot and snap over the teeth of the ratchet until the chain cannot be wound tighter. The pawl quickly assumes its normal position when lifted by the teeth of the ratchet, owing to its greater weight 15 being on the ratchet-wheel side, and it will be plainly seen, that the strain of the reverse movement of the windlass, is resisted directly through the body of the pawl and upon the supporting plate. The pivots of 20 the pawl and its operating arm will not be affected. To release the pawl 6 from the ratchet, the lock 8 is first operated clockwise, which releases the arm 20, then a slight pressure on the end of said arm will 25 withdraw the pawl 6 from engagement with the ratchet and the windlass is then free to turn so that the load will be dumped. It is obvious, that when the windlass is to be re-wound, the lock 8 is operated anti-clockwise, lifting the arm 20 and sliding the 30 pawl once more in position for engagement with the ratchet, and it cannot be moved from this engaging position until the lock 8 is first operated, therefore, any accidental 35 displacement, through vibration or otherwise, is avoided.

Having thus fully described the invention, what is claimed is:—

1. In a device of the character described, 40 a ratchet, a stationary support, a pawl mounted for edge to edge slidable engagement with said support, and means for bodily shifting said pawl back and forth on said edge, said pawl being mounted in a 45 manner relatively to said support as to cause the load imposed thereon to be carried directly by the support.
2. In a device of the character described, 50 a ratchet, a stationary support, a pawl mounted for edge to edge slidable engagement with said support, coöperating means on said pawl and support for guiding said pawl in its sliding movements, and means for bodily shifting said pawl on said support, 55 said pawl being mounted in a manner relatively to said support as to cause the

load imposed thereon to be carried directly by the support.

3. In a device of the character described, a ratchet, a stationary support, a pawl mounted for edge to edge slidable engagement with said support, and means pivoted to said support for shifting said pawl thereon, said pawl being pivoted to said shifting means and mounted in a manner relative to said support as to cause the load imposed 60 on said pawl to be carried directly by the support.

4. In a device of the character described, a ratchet, a stationary support, a pawl mounted for edge to edge slidable engagement with said support, means pivoted to said support for shifting said pawl thereon, said pawl being pivoted to said shifting means and mounted in a manner relative to 70 said support as to cause the load imposed on said pawl to be carried directly by the support, and a locking means for engaging said shifting means to retain said pawl in an operative position.

5. In a device of the character described, 80 a ratchet, a stationary support, a pawl mounted for edge to edge slidable engagement with said support, means pivoted to said support for shifting said pawl thereon, said pawl being pivoted to said shifting 85 means and mounted in a manner relative to said support as to cause the load imposed on said pawl to be carried directly by said support, a locking means for engaging said shifting means to retain said pawl in an 90 operative position, and coöperating means on said locking means and the support for limiting the throw of said locking means in one direction.

6. In a device of the character described, 95 a ratchet, a stationary support, a pawl mounted for edge to edge slidable engagement with said support, and means for shifting said pawl on said support, said pawl being mounted in a manner relative 100 to said support as to cause the load imposed on said pawl to be carried directly by said support and also being provided with a cut-away front portion whereby it can tilt in one direction to ride over the ratchet teeth. 105

In testimony whereof I affix my signature in presence of two witnesses.
